SAFETY CAP FOR BALL PLAYERS

Victor Brunzell, Long Island City, N. Y.

Application January 19, 1939, Serial No. 251,687

1 Claim. (Cl. 2—3)

This invention relates to headgear, and more particularly to head protecting devices for individuals who engage in sports, such as the game of baseball.

6 Baseball players and others engaged in similar sporting endeavors are frequently victims of serious and even fatal injuries caused, when pitched or batted balls come into violent contact with the head of the player, especially in the 10 region of the temples. The caps that are now commonly worn by players offer no protection against such injuries.

15 It is therefore an object of this invention to provide a cap, having means for protecting the wearer against injury caused by being hit by a rapidly moving ball, especially in the region of the temples.

20 To these ends the invention consists of a ball player's cap or similar headgear having, as a unit, a band portion and a peak for protecting the head against injury.

25 A further object lies in the provision of a cap or similar headgear having, as a unit, a band portion and a peak, the peak being shaped concavo convexly in front, and planarly at the sides, whereby the sides are made substantially rigid and inflexible.

30 It is another aim to provide a headgear of this character having, as a unit a band of substantially hard material and a peak, being shaped concavely-convexly in front and having lateral, wing-like extensions at the sides, to protect the temples of the wearer.

35 A still further object of the invention is to provide a headgear having a band of hard material and a resilient band secured thereto, for absorbing and distributing the force of impact of a moving ball about the head of the player generally.

40 Yet another object of the present invention is to provide a cap for ball players having the protective and safety features hereinafter to be more fully described, and which, when compared with caps now commonly used for this purpose, will 45 be found to be almost identical in appearance and weight.

45 With the above objectives in view, as well as others which will become apparent as the description progresses, the preferred embodiment 50 of the present disclosure is illustrated in the accompanying drawing, in which:

55 Figure 1 is an elevational view of the preferred embodiment of the invention, in use.

Figure 2 is a bottom plan view of the frame thereof.

Figure 3 is a sectional view, taken on line 3—3 of Figure 2.

Figure 4 is a bottom plan view of a cap, constructed in accordance with the present invention.

Figure 5 is a sectional view through the cap, along line 5—5 of Figure 4.

Figure 6 is an enlarged fragmentary sectional view on line 6 of Figure 4.

Figure 7 is a detail view taken on line 7—7 of Figure 2.

Figure 8 is a detail view taken on line 8—8 of Figure 2; and

Figure 9 is a detail view taken on line 9—9 of Figure 2.

Referring in greater detail to the drawing, the numeral 10 indicates generally the frame of a cap, which consists of a substantially oval shaped band 11 of essentially hard material, such as hard fibre or the like, having formed integrally therewith a peak 12. The peak is formed concavo-convexly in front, and is provided with planarly shaped side portions 13, bent at a sharp angle, as at 13', for a purpose to be hereinafter described.

Referring now more specifically to Figure 1 of the drawing, the headgear 14 consists of a skull covering 15 made of textile fabric or other suitable material, and said skull covering is provided with the usual openings 16 for purposes of ventilation, as is well known in the art.

Continuous around the band 11 is a member 18 of resilient material, such as foam rubber, sponge rubber and the like, and there is also provided the usual sweat band 19, completely 35 encircling the resilient member 18.

In order to give positive protection to the regions of the temples, the peak 12 is provided with sharp bends, as at 13' between the side members 13 and the front member 12. Thus, when the cap is worn, that part thereof, which is intended to cover the region of the temples, is angularly offset and protrudes away from the temples, as can be seen in Figure 1 of the drawing. The construction of the peak, which provides for a concavo-convexly shaped front member and planarly shaped side members, causes the peak and the said side members to be completely rigid and inflexible.

The cap is assembled substantially in the following manner:

A piece of textile or other fabric is cut to conform to the shape of the human skull. In addition thereto, sufficient material is provided if desired, to permit the outer face of the front 55

portion 12 of the peak to be covered therewith, as at 17, as well as the inner face of the peak (not shown). Material also is provided to cover the outside of the band 11, as at 21, and the material is then bent inwardly to be cemented, glued or otherwise secured to the inner face of the said band 11. Thereupon the resilient member 18 is secured in a similar manner to the inner face of the material, and the sweat band 19 is secured to the resilient member. Obviously, these steps may be taken in an order other than that, which is here described, in order to produce the same results.

It will be seen that there is thus provided an extremely useful cap for baseball players which, due to the presence of a head encircling protective band, affords protection against injuries caused by the impact of a misdirected ball. Since the regions of the temples have been found to be the most vulnerable places in accidents of this kind, special protection for them has been provided in the presence, as a unit, of a head encircling band and a peak, shaped concavo-convexly in front, and planarly at the sides, rendering that part of the band intended to cover the temples, completely rigid and inflexible. There is also provided a shock absorbing resilient member, to absorb the force of the impact.

While the present invention has been illustrated and described as a cap for baseball players, its use is not thereby intended to be restricted, since obviously it may be used with the same highly desirable results in any other athletic endeavor, where the danger exists, that misdirected missiles may cause injury to the head of a participant, and it may even be used for ordinary street wear. Nor does applicant desire this disclosure to restrict him to the exact construction herein indicated, it being obvious that minor changes may be made within the scope of the appended claim, without departure from the spirit of this invention. For instance, the band may be made of wider cross-section than 15 illustrated, to protect a wider area of the head.

Having thus described the invention, what is claimed as new and desired to secure by Letters Patent, is:

A cap comprising a substantially rigid endless 20 truncated conical band having a downwardly offset peak at the front and lateral angularly downturned wing-like extensions at the ends of said peak integral therewith and with said band, a resilient band interjacent said rigid band, a 25 covering having its lower edges secured between said bands, and a sweat band secured to the inner surface of said resilient band.

VICTOR BRUNZELL.
